UNITED STATES PATENT OFFICE

135,037

DESIGN FOR A COMBINED CAMERA AND GRIP HOLDER THEREFOR

Ralph H. Munson, St. Paul, Minn.

Application December 8, 1941, Serial No. 104,529

Term of patent 14 years

To all whom it may concern:

Be it known that I, Ralph H. Munson, a citizen of the United States, residing at St. Paul, in the county of Ramsey and State of Minnesota, have invented a new, original, and ornamental Design for a Combined Camera and Grip Holder Therefor, of which the following is a specification, reference being had to the accompanying drawing, forming part thereof.

Figure 1 is a side elevational view of a combined camera and grip holder therefor showing my new design.

Figure 2 is a front elevational view of the same.

Figure 3 is a rear elevational view of the same.

Figure 4 is a side elevational view of the same on the side thereof opposite Figure 1.

The essential features of my design reside in the portions shown in full lines, the parts shown in broken lines in Figure 1 having been omitted from the other figures for convenience of illustration.

I claim:

The ornamental design for a combined camera and grip holder therefor, as shown and described.

RALPH H. MUNSON.
